WILLIAM S. KING

BY Geo. H. Strong

HIS ATTORNEY

UNITED STATES PATENT OFFICE.

WILLIAM S. KING, OF SAN FRANCISCO, CALIFORNIA.

CIGARETTE AND LIKE PAPER HOLDER.

No. 928,058.

Specification of Letters Patent. Patented July 13, 1909.

Application filed February 23, 1909. Serial No. 479,420.

To all whom it may concern:

Be it known that I, WILLIAM S. KING, a citizen of the United States, residing in the city and county of San Francisco and State 5 of California, have invented new and useful Improvements in Cigarette and Like Paper Holders, of which the following is a specification.

My invention relates to a device for de-10 tachably holding cigarette and like paper so that the sheets may be readily detached singly, without disturbing the remainder of the package within the holder.

It consists in a combination of parts, and 15 in details of construction which will be more fully explained by reference to the accompanying drawings, in which—

Figure 1 is a perspective view showing the device with the cover opened upwardly. 20 Fig. 2 is an inverted perspective view of the same. Fig. 3 is an enlarged detail of the elastic holding catch or button.

It is the object of my invention to provide a device for conveniently holding packages 25 of thin paper, such as cigarette paper so that the sheets may be removed singly without disturbing the remainder of the package. For this purpose I form a book or holder consisting of a sufficiently rigid base A, a cover

30 B, and an overlapping extension C, which, when the cover is closed, will pass over the edge and upon the back A. The back A is provided with a button 2, and the edge of the flap C is provided with an engaging head 3.

35 The parts A, B and C may be made of leather, or any desired flexible fabric, so formed as to be easily opened or closed, or they may be made of aluminum, or other light or convenient metal, hinged at the 40 angles in order to allow the easy opening and closing of these parts.

The holder consists of an elastic strap 4 which passes around the back, and substantially at the angle or hinge between the parts 45 A and B. One or both these parts may be notched as shown at 5, to admit the flexible strap, and to allow the cover to be opened and closed without disturbing the position of the strap. As shown in Fig. 1, the strap 50 is brought from this point forward diagonally across the package of papers 6, which rests upon the back A, as shown. The portions of the strap 4 which cross the top of this paper, converge, and are carried down over

the front edge of the package, thence across 55 the back and engage with the button 2. In order to apply or remove such a strap when required, and to hold it in place, I have shown the button 2 made hollow, and with suitable means for attaching it to the back A. On 60 one side of the button is left an opening as at 8; this opening being sufficient to allow the bight of the elastic 4 to be introduced, so that this portion of the elastic will be securely confined within the hollow head 2, and cannot 65 be disengaged or lost; at the same time it is removable and replaceable when desired.

The portions of the strap 4 extending diagonally across the top of the package 6, allows the portions that pass over the rear 70 ends, and around the junction of the base and cover portion, to be so separated that the top sheet of the package may be easily withdrawn from under the strap, without in any way disturbing the remaining papers. 75 This makes the device a great convenience for cigarette smokers, or for any one using a number of sheets of thin paper, which it is desirable to detach from packages containing a number of such sheets. 80

Having thus described my invention, what I claim and desire to secure by Letters Patent is—

1. A package holding device consisting of a base, a closable cover and flap, and an engaging snap button, an elastic band converging from the outer ends of the cover portion across the front of the package, and means connecting the bight of the strap with the securing button. 85

2. In a paper package holding device, a base, a cover flexibly connected therewith having a flap adapted to fold over the edge of the package to the back of the base, a snap button having one member fixed to the flap, 95 and the other to the base, said base member being grooved, and an endless elastic band passing around the junction of the cover and base, extending diagonally across the top of the package, and having its opposite bight 100 engaged with the slot in the button.

In testimony whereof I have hereunto set my hand in presence of two subscribing witnesses.

WILLIAM S. KING.
